DESIGN FOR A FISH BOWL OR SIMILAR ARTICLE

Charles P. Askew, Marion, Ind., assignor to The Canton Glass Company, Marion, Ind., a corporation of Indiana

Application March 19, 1935, Serial No. 55,953

Term of patent 3½ years

To all whom it may concern:

Be it known that I, Charles P. Askew, a citizen of the United States, residing at Marion, in the county of Grant and State of Indiana, have invented a new, original, and ornamental Design for a Fish Bowl or Similar Article, of which the following is a specification, reference being had to the accompanying drawing, forming part thereof.

Fig. 2 is a side elevation thereof, and Fig. 3 is an end view of the device.

I claim:

The ornamental design for a fish bowl or similar article, as shown.

CHARLES P. ASKEW.
